(57) **CLAIM**

The ornamental design for a candy vending machine as shown and described.

DESCRIPTION

FIG. 1 is a top, front and right side perspective view of a candy vending machine showing my new design; FIG. 2 is a top, rear and left side perspective view thereof; FIG. 3 is a bottom, rear and left side perspective view thereof; FIG. 4 is a front elevational view thereof; FIG. 5 is a right side view thereof; FIG. 6 is a rear elevational view thereof; FIG. 7 is a left side view thereof; FIG. 8 is a top plan view thereof; FIG. 9 is a bottom plan view thereof;

FIG. 10 is an enlarged view of portion 10 in FIG. 1; FIG. 11 is an enlarged view of portion 11 in FIG. 1; FIG. 12 is an enlarged view of portion 12 in FIG. 6; and, FIG. 13 is an enlarged view of portion 13 in FIG. 8.

The dashed broken lines in the drawings illustrate portions of the candy vending machine which form no part of the claimed design.

The dash-dot broken lines illustrate the boundary of the enlarged views and form no part of the claimed design.
